DESIGN FOR A COFFEE GRINDER
OR THE LIKE

David S. Isrin, New York, N. Y.

Application October 16, 1947, Serial No. 141,949

Term of patent 7 years

(Cl. D55—1)

To all whom it may concern:

Be it known that I, David S. Isrin, a citizen of the United States of America, and a resident of the city, county, and State of New York, have invented a new, original, and ornamental Design for a Coffee Grinder or the Like, of which the following is a specification, reference being had to the accompanying drawing forming part thereof, in which:

Figure 1 is a side elevation of a coffee grinder embodying my invention;

Figure 2 is a perspective view of the coffee grinder with the parts in an exploded position.

I claim:

The ornamental design for a coffee grinder or the like, as shown.

DAVID S. ISRIN.
